(57) CLAIM

The ornamental design for an automotive exterior grille, as shown and described.

DESCRIPTION

FIG. 1 is a perspective view of an automotive exterior grille shown on the left side of a vehicle shown in broken lines, the right side is a mirror image of that shown; and,

FIG. 2 is an enlarged front perspective view thereof.

The vehicle shown in broken lines are for illustrative purposes only and form no part of the claimed design.

1 Claim, 2 Drawing Sheets

FIG. 2
